(57) **CLAIM**

The ornamental design for a door for dishwasher as shown and described.

DESCRIPTION

FIG. 1 is a front perspective view of the door for dishwasher showing our new design;

FIG. 2 is a front view thereof;

FIG. 3 is a back view thereof;

FIG. 4 is a left side view thereof where the right side view is a mirror image;

FIG. 5 is a top plan view thereof;

FIG. 6 is a bottom plan view thereof;

FIG. 7 is a front perspective view showing the state of use that only the lighting part is protruded and the lighting is turned on;

FIG. 8 is a front perspective view in a condition that the handle has been protruded forward;

FIG. 9 is a front view of FIG. 8;

FIG. 10 is a back view of FIG. 8;

FIG. 11 is a left side view of FIG. 8 where the right side view is a mirror image;

FIG. 12 is a top plan view of FIG. 8;

FIG. 13 is a bottom plan view of FIG. 8; and,

FIG. 14 is a front perspective view showing the state of use that the lighting part is turned on.

The broken lines depict portions of the door for dishwasher that form no part of the claimed design.

1 Claim, 14 Drawing Sheets
